ROLLER STRIPPING APPARATUS

Percy Shaw, Boothtown, Halifax, England

Application February 12, 1948, Serial No. 7,879
In Great Britain December 6, 1946Section 1, Public Law 690, August 8, 1946
Patent expires December 6, 1966

5 Claims. (Cl. 15—256.5)

1

This invention relates to a stripping knife arrangement for stripping from a roller material which has been deposited thereon and removing it from such roller in sheet formation, and it has for its object to cause the stripping knife to make a sensitive contact, and follow without effort the surface of the roller under all conditions whether the roller is truly formed and is running truly, or is subject to some defect either in construction or in running as for example in the event of it not being circular, or not running truly, or partaking of a lateral movement due to play between the roller necks and their bearings and also to enable the knife to expand or contract freely when affected by variations in temperature which may be caused by the knife edge contacting with a hot roller and material intermittently or otherwise whilst still retaining its sensitivity of contact when in contact with the roller, and to prevent the knife from becoming distorted in the event of pressure being applied to it by a screw or other positive means, also to enable the knife to be capable of being quickly and easily moved to an operative position or an inoperative position in relation to the roller and to enable the amount of pressure that the knife exerts against the roller to be easily and accurately adjusted and when adjusted to exert that pressure each time it is moved to its operative position, without requiring further adjustment.

With the above and other objects in view the invention consists in the novel feature of construction and arrangement of parts hereinafter fully set forth and pointed out in the subject matter being claimed and shown in the accompanying drawings wherein:

Fig. 1 is an end elevation of a roller stripping apparatus constructed in accordance with this invention.

Fig. 2 is a front view of the apparatus shown in Fig. 1.

Fig. 3 is an end view of the pivot bar and knife drawn to a larger scale, and

Fig. 4 is an end view of one end of the pivoted weight carrying frame shown in Fig. 1.

A, B indicate a pair of rollers on the top and between the nip of which the material to be converted into sheet formation is placed in a plastic condition. These rollers revolve in the directions indicated by the arrows in Fig. 1 and they are both heated, the roller B being heated to a higher temperature than the roller A, the result being that the material clings to the roller B. The roller A is supposed to be mounted in fixed bearings and the roller B in movable bearings which allow it to be adjusted towards and away from the roller A in order to regulate the thickness of the material that is deposited thereon and which has to be stripped therefrom by the stripping knife C. This knife is fixed to a

2

pivot bar D by screws D¹ which pass through countersunk clearance holes C¹ in the knife and through tapped holes in the pivot bar D. The ends of the latter are formed with journal pins D² which are free to turn in bearings in plates E that are fixed to the roller bearing blocks F in which the journals B¹ of the roller B are journaled.

Screwed or otherwise attached to the pivot bar D are two rails G which may be T-shaped in cross section as shown in Fig. 4 and attached to these rails are two open rectangular frames G¹ consisting of longitudinal and transverse members. These rails extend transversely across the pivot bar at each side of the pivot D² and are interconnected by a member G² and constitute with such pivot a two-armed lever device having a short arm and a long arm and extending through the openings in the frames is a shaft H on the ends of which are fixed rollers H¹ which are free to run along the rails G as shown in Fig. 4 and act as weights.

Fixed to each frame G¹ is a transverse member J which acts as a stop for the roller shaft and can be fixed in any one of a number of different positions by means of bolts J¹ passed through any one of a number of holes G³, Fig. 1, in the longitudinal members and secured by nuts J³, Fig. 4.

With this arrangement when the rollers H¹ occupy a position on the short arms of the rails G they tilt the pivot bar D to move the knife C out of contact with the roller B as shown by the dotted lines in Fig. 1.

To bring the knife into contact with the roller the long arm or arms of the rails are moved downwardly by hand or otherwise until they incline in the opposite direction and the weighting rollers then run down the rails by gravity and cause the knife to bear against the surface of the roller with a pressure which is determined by the stops J which can be fixed in any adjusted position along the long arm of the rail or rails to limit the travel of the weighted roller or rollers.

If desired sliding weights may be substituted for the rollers H¹ and one or more intermediate weights may be fixed on the shaft H.

What I claim as my invention and desire to secure by Letters Patent of the United States is:

1. In a roller stripping apparatus comprising support means and having a stripping roller rotatably supported by the support means, the combination of a pair of bearings mounted on said support means in axial parallelism with the stripping roller; a stripping knife having end portions forming a pivot axis pivotally mounted in said bearings to be rockable toward and away from said stripping roller, said stripping knife being radially pendant from said pivot axis; an elongated rocking frame rigid with the upper portion of said stripping knife and extending

transversely across the latter a predetermined distance inwardly past the pivot axis thereof toward said stripping roller and also a predetermined distance in the opposite direction past said pivot axis away from said stripping roller; a movable weight member supported on said rocking frame and adapted to move upon the latter from one side of said pivot axis to the other side thereof; and means for guiding said weight member in movement on said rocking frame.

2. In a roller stripping apparatus comprising support means and having a stripping roller rotatably supported by the support means, the combination of a pair of bearings mounted on said support means in axial parallelism with the stripping roller; a pivot bar parallel to said stripping roller terminating in a pair of journal pins extending rotatably into the bearings; a stripping knife rigidly secured to said pivot bar in parallelism with said stripping roller and pendants rockable toward and away from the same stripping roller; an elongated rocking frame rigid with the upper portion of said stripping knife and extending transversely across the latter a predetermined distance inwardly past the pivot axis thereof toward said stripping roller and also a predetermined distance in the opposite direction past said pivot axis away from said stripping roller; a travelling weight member movably supported on said rocking frame and adapted to move upon the latter from one side of said pivot axis to the other side thereof; and means for guiding said weight member in movement on said rocking frame.

3. In a roller stripping apparatus comprising support means and having a stripping roller rotatably supported by the support means, the combination of a pair of bearings mounted on said support means in axial parallelism with the stripping roller; a pivot bar parallel to said stripping roller terminating in a pair of journal pins extending rotatably into the bearings; a stripping knife rigidly secured to said pivot bar in parallelism with said stripping roller and pendants rockable toward and away from the same stripping roller; a substantially straight elongated rocking frame rigidly secured upon the pivot bar and forming a runway extending transversely across said pivot bar a predetermined distance inwardly past the pivot axis thereof toward said stripping roller and a predetermined distance in the opposite direction past said pivot axis away from said stripping roller; a movable weight member supported on said rocking frame and adapted to move upon the latter from one side of said pivot axis to the other side thereof; and means for guiding said weight member in movement on said rocking frame or runway.

4. In a roller stripping apparatus comprising support means and having a stripping roller rotatably supported by the support means, the combination of a pair of bearings adjustably mounted on said support means in axial parallelism with the stripping roller; a pivot bar parallel to said stripping roller terminating in a pair of journal pins extending rotatably into the bearings; a stripping knife rigidly secured to said pivot bar in parallelism with said stripping roller and pendants rockable toward and away from the same stripping roller; a pair of substantially straight parallel rails rigidly secured upon the pivot bar and extending transversely across the latter, the two parallel rails being interconnected and forming together with the pivot pin upon said pivot bar a two-armed rocking lever device of the

first order having two short lever arms extending toward said stripping roller and two relatively longer lever arms extending away from the latter; two open rectangular and elongated frames extending along and fixed upon said rails in mutual parallelism; a shaft extending freely through the openings in the elongated frames in parallelism with said stripping roller; and a pair of weight rollers fixed on said shaft in spaced apart relation and resting on said rails in such manner as to be free to roll along these rails when the latter are tilted in one direction or the other and effective to retain the stripping knife in substantially tangent stripping contact with said stripping roller when the rails and elongated frames are tilted down at the outer end of the lever device remote from said stripping roller and to rock said stripping knife out of contact with said stripping roller when said rails and elongated frames are tilted in the opposite direction.

5. In a roller stripping apparatus comprising support means and having a stripping roller rotatably supported by the support means, the combination of a pair of bearings adjustably mounted on said support means in axial parallelism with the stripping roller; a pivot bar parallel to said stripping roller terminating in a pair of journal pins extending rotatably in the bearings; a stripping knife rigidly secured to said pivot bar in parallelism with said stripping roller and pendants rockable toward and away from the same stripping roller; a pair of substantially straight parallel rails rigidly secured upon the pivot bar and extending transversely across the latter, the two parallel rails being interconnected and forming together with the pivot pin upon said pivot bar a two-armed rocking lever device of the first order having two short lever arms extending toward said stripping roller and two relatively longer lever arms extending away from the latter; two open rectangular and elongated frames extending along and fixed upon said rails in mutual parallelism; a shaft extending freely through the openings in the elongated frames in parallelism with said stripping roller; a pair of weight rollers fixed on said shaft in spaced apart relation and resting on said rails in such manner as to be free to roll along these rails when the latter are tilted in one direction or the other and effective to retain the stripping knife in substantially tangent stripping contact with said stripping roller when the rails and elongated frames are tilted down at the outer end of the lever device remote from said stripping roller and to rock said stripping knife out of contact with said stripping roller when said rails and elongated frames are tilted in the opposite direction; and an adjustable stop mounted on the longer lever arms of the rocking lever device for determining the position of the weight rollers along said longer lever arms or rails, in order to regulate the amount of pressure to be exerted by the stripping knife on the stripping roller for performing the stripping operation.
